UNITED STATES PATENT OFFICE

HERBERT W. OWEN, OF DOVER, NEW HAMPSHIRE.

MAGAZINE-TOOL LOADER

1,054,788.

Specification of Letters Patent. Patented Mar. 4, 1913.

Application filed March 22, 1912. Serial No. 685,532.

To all whom it may concern:

Be it known that I, HERBERT W. OWEN, of Dover, in the county of Strafford and State of New Hampshire, have invented certain new and useful Improvements in Magazine-Tool Loaders, of which the following is a specification.

This invention relates to apparatus for gathering small articles, such as the travelers for spinning rings, and assembling them on or delivering them to a carrier which will support a multiplicity of the articles in a magazine tool.

The object of the invention is to provide a simple, efficient and rapidly operating device or apparatus which will select the articles from a large quantity in a holder and deliver them in a row or series.

To these ends the invention consists in the apparatus substantially as hereinafter described and claimed.

Of the accompanying drawings:—Figure 1 is a plan view of the improved apparatus in one of its embodiments. Fig. 2 represents a section on line 2—2 of Fig. 1. Fig. 3 represents a section on line 3—3 of Fig. 1 on a larger scale. Fig. 4 is a detail elevation of the plow or collecting end of the runway looking from a point indicated by the line 4—4 in Fig. 1. Fig. 5 represents a section on line 5—5 of Fig. 1. Fig. 6 is a perspective view of the plow or collecting end of the runway. Fig. 7 is a detail sectional view illustrating the delivery end of the runway and one end of the magazine carrier which is to be supplied with the articles pushed along the runway.

Similar reference characters indicate the same or similar parts in all of the views.

A suitable frame or casting 10 is provided with a bearing 11 for a vertical shaft 12 to the upper end of which is secured the carrier or holder 13 having an annular trough-shaped upper surface to receive a mass or quantity of the articles and separators as indicated in Fig. 3. To the lower end of the shaft 12 is secured a bevel pinion 14 which meshes with a bevel pinion 15 on a horizontal shaft 16 mounted in suitable bearings in the base of the frame. The shaft is provided with a hand wheel 17 by means of which said shaft and, through the gearing described, the carrier or holder 13 may be rotated. Secured to rotate with the holder 13 are two spring arms 18, 19, the former

being shorter than the latter, said spring arm 19 having one side of its tip provided with a slightly curved bevel, as at 20. The arms 18, 19 may be of one piece of spring steel, or they may be made of separate pieces. 50 The extreme end of the long arm 19 is adapted to reach above the top edge 21 of the frame 10, and to ride on certain portions of the latter at times, as hereinafter described. Said arms are secured to the 65 holder 13 by suitable means, such as screws 22. The runway 23 has a tangential portion which is supported by the edge 21 of the frame, the outer end of said runway being shown as provided with a hole 24, said hole 70 being simply for the purpose of enabling a receiver for the articles to be readily fitted in alignment with the delivering end of the runway. From the tangential portion, the runway is substantially concentric with the 75 axis of rotation of the holder for nearly a complete circle, the other end of said runway dipping into the holder, as shown in Figs. 2, 3 and 4. This inner or receiving end of the runway is provided with a plow 80 or thickened portion 25, the upper edges of which form shoulders 26, (see Fig. 6). Above the thickened or plow end 25 is a vertical relatively thin blade 27, and the runway is provided with beveled shoulders 28 85 on opposite sides of the blade 27. On each side of the blade 27 is a space or throat 29 between the under edges of the runway below the shoulders 28 and the upper edges or shoulders 26 of the plow 25. An end portion of a bar 30 is indicated in Fig. 7, said bar having a pin to enter the hole 24 in the delivering end of the runway. Said bar 30 is intended to merely represent the magazine carrier of a tool which is to be supplied 95 with the articles in the rotary holder, said articles in the present case being travelers for spinning rings, such travelers being indicated at *a* in Figs. 3, 4, and 5. The complete tool having the magazine carrier is described and claimed in my application, Serial No. 685,533, filed on even date herewith.

In the annular trough in the rotary holder or carrier 13 a large quantity of the separators 31 will be placed as indicated in Fig. 105 3. These separators may be balls of different sizes, such as shot. I do not limit myself to the separators being perfect spheres, it being chiefly essential that they shall be of such shape that they cannot become engaged 110

with a runway. Although they are loose in the holder, they are permanent parts of the mechanism or apparatus.

In operation, the articles, such as travelers 5 *a*, are dumped into the holder 13 and said holder is then rotated in the direction of the arrow in Figs. 1 and 4. This movement carries the articles and the separators around in such direction that the receiving 10 or plow end of the runway which dips into the mass will stir up the articles and separators and some of the articles will find their way in succession onto the blade 27, straddling the latter, and the continued motion of 15 the separators will result in the articles being worked along the upper edge of the blade 27 onto the portion of the runway beyond the shoulders 28. None of the articles excepting those properly positioned can be 20 carried onto the runway because if they are not properly positioned, one or the other of the inwardly bent ends of the articles will ride up on the shoulder 28 so that that article will be tipped off and fall back into the 25 mass. Those articles which are properly positioned will be carried along with their inwardly bent ends passing through the throats 29, and will reach a portion of the runway from which they cannot become 30 disengaged laterally. The upward inclination of the dipping end of the runway is such that the articles selected out from the mass and worked upwardly onto the runway above the blade 27 will be engaged by the 35 edge of the blade 18 and pushed farther along up the incline of the runway, said blade, owing to its light spring nature, being readily flexed to follow the upward inclination. When the blade 18 reaches the 40 highest portion of the runway, it will have become then so curved that it slips off and springs back to a horizontal position, leaving an article that has been pushed up by it resting on the high portion. Then the 45 blade or spring arm 19 follows and pushes along any article or articles that have been left on the runway, the curved edge 20 of said arm 19 finally pushing such article or articles outwardly along the tangential portion of the runway, leaving them on that 50 portion, if there are but two or three articles assembled near the outer end, but finally acting through an accumulation of such articles to push them off from the end and 55 onto the end of the magazine carrier 30, which magazine carrier can then be transferred to the tool which is to be used to apply the articles.

While I have shown spinning ring travelers as the articles to be assembled and loaded onto a separable carrier, it is to be understood that the invention is not limited thereto, as various other articles, such as staples for use in a magazine stapling tool 60 might be assembled and loaded in the same

manner as described in connection with the ring travelers.

Infrequently a traveler will be pushed along the runway with another one hooked into and depending from it. To prevent such inter-engaged articles being fed out or loaded onto the bar 30, the thicker upper edge of the runway is cut away or recessed on both sides, near its delivery end, as shown at 32. With this provision, any such inter-engaged articles will be discharged from the runway before reaching the end thereof, and drop back into the holder. This is because the lower or hanging article will engage the inner corner of the top edge of the 75 frame and be held back so that the end of the arm 20 will dislodge the upper article and both will drop off from the runway. Even if additional articles are occasionally pushed off, the operation of the loader is 80 sufficiently rapid to quickly deliver the required number. 85

An especial advantage of the loader as a whole, including the separators 31, is that there can never be an entanglement of a 90 large number of the travelers. In operation the plow picks up but one at a time, and inter-hooking of another one occurs but rarely.

I claim:

1. A loading apparatus comprising a holder for the articles, a plurality of loose separators in the holder, a runway having a receiving end dipping into the holder, and means for causing a relative movement of 100 the holder and runway to transfer the articles from the holder to the runway.

2. A loading apparatus comprising a holder for the articles, a plurality of loose separators in the holder, a runway having a receiving end dipping into the holder, means for causing a relative movement of 105 the holder and runway to transfer the articles from the holder to the runway, and means for pushing along on said runway, 110 the articles that accumulate thereon.

3. A loading apparatus comprising a rotary holder for small articles, a plurality of loose separators in said holder, a runway having a receiving end dipping into the 115 holder, and a spring arm carried by said rotary holder and adapted to ride along the runway to advance the articles toward the discharge end of the runway.

4. A loading apparatus comprising a rotary member having a trough-shaped receiver or holder for small articles, a pair of spring arms projecting over said trough-shaped holder and rotatable therewith, a stationary runway mounted over the trough-shaped holder and having a receiving end dipping into the holder and having a tangential discharge end. 120

5. A loading apparatus comprising a rotary member having a trough-shaped re- 130

- ceiver or holder for small articles, a pair of
spring arms projecting over said trough-
shaped holder and rotatable therewith, a
stationary runway mounted over the trough-
shaped holder and having a receiving end
dipping into the holder and having a tan-
gential discharge end, the receiving end of
the runway having means for properly posi-
tioning the articles thereon.
- 5 6. Apparatus for assembling spinning
ring travelers, comprising a holder for a
quantity of the travelers, a plurality of
loose, disconnected members in said holder
to commingle with and to separate the
travelers from each other, and an elongated 15
receiver arranged to dip into the mass of
travelers and loose separating members and
remove the travelers successively therefrom.
In testimony whereof I have affixed my
signature, in presence of two witnesses.
